(57) CLAIM

The ornamental design for a flooring for building as shown and described.

DESCRIPTION

The patent or application file contains at least one drawing executed in color. Copies of this patent or patent application publication with color drawing(s) will be provided by the Office upon request and payment of the necessary fee.

FIG. 1 is a plan view showing a flooring for building showing my new design; and,

FIG. 2 is an enlarged view of a portion identified in rectangle 2 of FIG. 1.

The broken lines depict the boundaries of the claimed design and form no part thereof.

1 Claim, 2 Drawing Sheets
(2 of 2 Drawing Sheet(s) Filed in Color)
